UNITED STATES PATENT OFFICE.

ARTHUR D. COLTON, OF CHICAGO, ILLINOIS.

THERMOSTAT.

No. 813,403.

Specification of Letters Patent.

Patented Feb. 27, 1906.

Application filed August 22, 1904. Serial No. 221,785.

To all whom it may concern:

Be it known that I, ARTHUR D. COLTON, a citizen of the United States, residing at Chicago, in the county of Cook and State of Illinois, have invented certain new and useful Improvements in Thermostats, of which the following is a specification.

My invention relates to thermostats for controlling electrical circuits to the usual and well-known temperature-regulating apparatus or devices employed for operating valves to admit steam or hot water to radiators and the like or for controlling the dampers of a furnace whereby the temperature of a room may be maintained at a predetermined degree.

The object of my invention is to produce a simple and inexpensive but efficient and reliable thermostat and also to provide means for bodily shifting or adjusting the electrical contacts with relation to a circuit-closer, which adjustment is in addition or supplemental to their independent adjustment toward and away from each other.

In the drawings, Figure 1 is an elevation of my improved thermostat; Fig. 2, a side elevation thereof; Fig. 3, a sectional elevation on the line 3-3 of Fig. 2, such section being taken just within the line of the face-plate to expose the parts therewithin; Fig. 4, a plan view of the thermostat, and Fig. 5 a detailed view of one of the working parts.

It will be understood that the parts illustrated in the drawings are simply the interior parts of the thermostat proper and that such parts are in practice incased in a suitable casing, which is generally of an ornamental character; but as such casing is immaterial to an understanding of the invention the same has not been illustrated.

As herein shown, the thermostat comprises a base-plate 1, on which the various operating parts are mounted and which carries in front thereof a face-plate 2, secured to the plate 1 by means of screws 3, passing through distance-sleeves 4. The face-plate has formed thereupon (or attached thereto as a separate member) an indicating-scale, as shown in Fig. 1. It is obvious, however, that the construction just described represents mere mechanical details, which can be varied as desired.

The expansible and contractible member consists of a longitudinally-extending strip 5, preferably of hard rubber, and secured at its lower end to a block 6, fastened to or formed integral with the base-plate. Toward its up-

per end this strip works freely through an opening in a guide-lug 7, above which its end projects. This upper end is provided with a cap or sleeve 8, having a projecting arm 9, 60 extending obliquely toward the center line of the thermostat for connection with the circuit-closer, as hereinafter explained.

The circuit-closer comprises a longitudinally-extending vertical bar 10, pivoted at its upper end on a pivot-pin 11, which has its bearing respectively in the base-plate and in an angle-plate 12, secured to such base-plate, as indicated in Figs. 3 and 4. This bar has a short arm 13, extending laterally from its upper end and pivotally connected to the upper or free end 9 of the sleeve 8. It will be seen that owing to the connection of the expandible member 5 to the short arm of the circuit-closer, which is, in effect, a lever, a slight movement of the strip or member 5 will be multiplied at the lower end of the lever or circuit-closer, which plays between the electrical contacts hereinafter described.

For the purpose of maintaining the circuit-closer or lever in a normal position intermediate the contacts and a certain predetermined distance from the strip or member 5 I provide a coil-spring 14 and interpose the same between the strip 5 and the circuit-closer or bar 10, as clearly indicated in Fig. 3.

Electrical contacts 15 and 16 are carried on the ends of the adjusting-screws 17 and 18, respectively, which pass diametrically through the two similar posts 19, respectively. The lower end of the circuit-closer or bar 10 depends between these contacts, as described, and is normally positioned at an intermediate position out of contact with either one of such contacts, as seen in Fig. 3. 95

The two posts 19 instead of being secured or connected with the base-plate in fixed relation therewith are mounted upon a flat plate 20, made of insulating material, preferably hard rubber, and arranged to slide 100 transversely of the base-plate in a guideway formed in suitable manner, as by means of screws 21, properly disposed for that purpose. By preference a thin binding-strip 105 of metal 22 is arranged on the upper edge and around the upper corner of the plate 20.

The plate 20 is, in fact, a rack, inasmuch as it is provided on its lower edge with teeth 23, which are engaged by the teeth of a pinion or segment 24. (Illustrated in detail in Fig. 5.) This segment is formed on a shaft or rod 25, having bearings in the plates 1 and

2 and extending beyond the latter plate, where it is provided with a cross-pin 26 to enable the shaft to be easily turned or adjusted by the operator.

- 5 The shaft 25 carries an indicator or pointer 27, which extends upwardly and is movable over the face of the dial formed on the face-plate 2, Fig. 1. It will be understood that this pointer is adjusted to a position corresponding with the temperature desired in the room. For instance, in Fig. 1 this pointer now indicates 70 degrees, which is the desired temperature; but in case a temperature of 75° is desired this pointer is moved to the right, Fig. 1, until it indicates or points to "75" on the dial. It will be observed, however, that in this movement or adjustment of the pointer the rack has likewise been shifted to the right, with the result that the post 19 and the electrical contacts 15 and 16 carried thereby are bodily shifted with relation to the circuit-closer or bar 10. Consequently one of the electrical contacts will be relatively nearer to bar 10 than the other, with the result that on a slight lowering of the temperature the circuit will be closed and the temperature thereby maintained at the desired degree.

It is obvious that the distance between the two contacts is adjusted by means of the screws 17 and 18 and also that such adjustments are independent. As soon as the proper adjustment of these screws is made such screws are locked in set position by means of set-screws 28, entering the top of the posts 19 and adapted to bear against the adjusting-screws. To accommodate the movement of the rack 20, the face-plate is provided with slots 29, through which the set-screws 28 pass.

The electrical connections are made in the usual way, in the present instance two of the wires or connections (not shown) being connected with the adjusting-screws 17 18, and therefore to the electrical contacts 15 and 16, and the third wire or connection being connected with the base-plate 1, with which the circuit-closer or bar 10 is also in electrical contact through the metallic connections described.

The thermostat herein shown and described is comparatively simple in construction and reliable and efficient in operation. Moreover, the construction is such that after the contacts are set or adjusted to the proper distance apart such distance may be maintained, although the contacts are shifted bodily to provide for an increased or decreased degree of temperature.

60 I claim—

1. The combination with a base-plate, 1, of a circuit-closer arranged therein and comprising a strip, 5, of expansible and contractible material and secured at its lower end to said base-plate, a supporting-lug, 7, secured

70 to the base-plate and loosely engaging said strip, a bell-crank-shaped lever pivoted to said base-plate and having a long arm, 10, and a short arm, 13, a cap-piece or ferrule, 8, engaging the upper end of said strip and having an extension or arm, 9, engaging the short arm, 13, of the bell-crank, and electrical contacts, 15 and 16, between which said long arm, 10, is adapted to operate; substantially as described.

75 2. The combination with a base-plate, 1, of a circuit-closer arranged therein and comprising a strip, 5, of expansible and contractible material and secured at its lower end to said base-plate, a supporting-lug, 7, secured 80 to the plate and loosely engaging said strip, a bell-crank-shaped lever pivoted to said base-plate and having a long depending arm, 10, and a short arm, 13, a cap-piece or ferrule, 8, engaging the upper end of said strip and having an extension or arm, 9, engaging the short arm, 13, of the bell-crank, and a coiled spring, 14, secured at one end to the strip, against the other end of which spring the long arm, 10, is adapted to contact; substantially as de- 90 scribed.

85 3. A thermostat comprising a base-plate, a rod of expansible and contractible material, a block mounted on the base-plate and to which one end of said rod is secured, a lug 95 supporting the other end of said rod and through which the same is adapted to slide, a bell-crank lever fulcrumed to the base in proximity to the movable end of said rod, a connection from said end to the short arm of the lever, two electrical contacts with which the long arm of said lever is adapted alternatively to engage, a sliding plate upon which said contacts are mounted, said plate being provided with rack-teeth on one edge, 100 a shaft carrying a segment engaging said rack-teeth, and a handle mounted on said shaft and adapted to move the same to move the plate and pointer.

105 4. A thermostat comprising a frame, two perforated lugs mounted thereon, a thermostatic rod with its two ends passing through said lugs, means for clamping one end of said rod to its associated lug, whereby the rod may be readily adjusted with relation to or removed from said lug, a bell-crank lever fulcrumed to the frame in proximity to the other lug, a connection between the free end of the rod and the short arm of said lever, the long arm of the lever extending parallel to said thermostatic rod, and an adjustable electrical contact with which the end of said long arm is adapted to engage.

115 5. A thermostat comprising a base-plate, a thermostatic rod having one end immovably 120 and the other end slidably mounted on said base-plate, a contact-arm fulcrumed to the base-plate in proximity to the free end of said rod, a connection between said end and said contact-arm, contact-points arranged in 130

proximity to the other end of said rod, and with which the free end of said arm is adapted to engage, a movable mounting for said contact-points, and a pointer operatively connected with said movable mounting and adapted to move therewith, said thermostatic rod, contact-arm and pointer being arranged parallel to each other and to the base, whereby a compact structure is obtained.

6. A thermostat comprising a base-plate and a face-plate, a thermostatic rod mounted on the base-plate, a contact-arm mounted on the base-plate and arranged to be moved by the expansion or contraction of said thermo-

static rod, two contact-screws with the points 15 of which said contact-arm is adapted alternatively to engage, the heads of said screws projecting beyond the frame of said thermostat, and set-screws adapted to engage said contact-screws, the heads of said screws projecting through said face-plate into an accessible position, whereby the adjustment of the thermostat may be readily varied.
